UNITED STATES PATENT OFFICE.

JOHN A. LAMONT, OF GRANITE CITY, ILLINOIS, ASSIGNOR TO AMERICAN STEEL
FOUNDRIES, OF NEW YORK, N. Y., A CORPORATION OF NEW JERSEY.

SIDE FRAME.

1,146,886.

Specification of Letters Patent. Patented July 20, 1915.

Application filed April 22, 1915. Serial No. 23,030.

To all whom it may concern:

Be it known that I, JOHN A. LAMONT, a citizen of the United States, and resident of Granite City, in the county of Madison and State of Illinois, have invented certain new and useful Improvements in Side Frames, of which the following is a specification.

My invention relates to railway cars, and has particular reference to a novel built-up side frame for use in connection with car trucks.

An object in the construction of the present device is to provide for economy in cost of construction. This economy is the result of the use of commercial rolled sections which are fabricated to form a substantially integral side frame structure.

A further object is to lessen the weight of such structures by so disposing the metal thereof that the greatest possible resistance is secured with minimum weight. In the present structure the principal parts of the truss, namely—the compression and tension members, are formed from commercial rolled shapes, the remainder of the parts being formed by casting in steel or malleable iron.

The invention will be more readily understood by reference to the accompanying drawings, wherein—

Figure 1 is a side elevation of a portion of a side frame constructed in accordance with my invention, Fig. 2 is a plan view thereof, with the top or compression member partially broken away, Fig. 3 is a similar plan view showing the parts in their assembled relation, Fig. 4 is a view similar to Fig. 1, showing a slightly modified construction, Fig. 5 is a plan view of the construction shown in Fig. 4, with the compression member broken away, and Fig. 6 is a fragmentary elevation partly in section showing a further modification.

Referring more particularly to Figs. 1, 2 and 3, it will be seen that I provide a compression member 10 of generally channel shape, a tension member 11 of T-shape, and a strut member 12 in the form of a casting. The ends of the compression and tension members are tied together by the use of a casting 13.

The compression member, as stated, is in the form of a channel, and at the ends thereof the web 14 is continued beyond the termination of the flanges, forming a tongue or extension which is bent downwardly, as later described.

The strut member is so formed as to provide columns having bolster guides 15 and a spring seat 16, the space between the two columns being enlarged at the point 17 to permit the insertion of a bolster having side lips or flanges. The upper portion of the strut member 12 is provided with a connecting web 18 which is riveted to the channel compression member.

The T-shaped tension member is inserted within a similarly shaped aperture in the casting 13, the flange of the member being terminated at the point 19 in Fig. 1, the remaining portion 20 of the member continuing past the sheared off end of the flange and being bent downward into engagement with the casting 13, the lip 14 of the compression member and said extension 20 of the tension member being secured to the casting by rivets 21.

The casting which unites the ends of the truss is provided with an upwardly extending filler or brace portion 22 which lies between the tension and compression members and is secured to the web of the compression member by means of the rivets 23. The casting is preferably in the form of a pedestal providing jaws 24, 25 between which a journal-box 26 may be held.

In the construction shown in Figs. 4 and 5, the tension and compression members do not actually come in contact. The compression member 27 is formed from a commercial channel, as in the construction heretofore described, and both the web and flanges thereof terminate at the point 28 abutting against a shoulder 29 formed on the casting 30. The web of the channel is securely riveted to an upward extension 31 of the casting. The tension member 32 is likewise of channel shape, the metal flanges of the channel being suitably sheared off and terminating at the point 32, the remaining portion of the member continuing and being bent downward, as at 34, a rivet 35 securing this portion to the casting. The tension member is accommodated within a properly shaped recess in the casting and is secured thereto by means of rivets 36. The strut member 37 is similar to that described in connection with Figs. 1 to 3.

In Fig. 6 the compression member 39 is of rolled channel form, the flanges thereof being terminated short of the end, leaving the web 40 to continue onward and abutting against a shoulder 41 on the casting 42. The

tension member 43 is of channel shape, its side flanges being cut off, the web 44 of the member continuing on and being bent downward into a recess or notch 45 in the casting. In this case I have shown the journal-box as integral with the casting, it being understood that this is an alternative construction with relation to all of the forms shown.

10 In each case it will be seen that the parts, when assembled and riveted, form a substantially integral structure, the disposition of metal being such that the greatest resistance to strains is secured with the least weight. Furthermore, it will be understood that the rolled shapes employed lend themselves readily to the formation of a truss such as described. In each of the cases shown and described, the casting which is used to unite the ends of the truss is threaded onto the end of the tension member and that thereafter the end of the tension member is bent downward, preferably while hot, into its final position.

15 25 It will be understood that wherever I have referred to the use of rolled shapes that pressed shapes might be used with equal facility and that therefore I consider the terms rolled and pressed as synonymous.

30 I claim:

1. In a side frame, the combination of tension member, compression member and strut, and a casting in the form of a journal box pedestal within which the end of said tension member is fitted and against which said compression member abuts, and means for rigidly securing said members and said casting together, substantially as described.

40 2. In a side frame, the combination of tension member, compression member and strut, and a casting in the form of a journal box pedestal within which said tension member is fitted and against which said compression member abuts, a portion of said tension member being bent downward and secured to said casting, substantially as described.

3. In a side frame, the combination of tension member, compression member and strut, and a casting in the form of a journal box pedestal within which said tension member is fitted and against which said compression member abuts, a portion of said tension member being bent downward and hooked over a portion of said casting, substantially as described.

4. In a side frame, the combination of tension member, compression member and strut, and a casting in the form of a journal box pedestal with which said tension member engages and against which said compression member abuts, a portion of said tension member being bent over and in holding en-

gagement with said casting, whereby a portion of the pull of said tension member is absorbed by said casting independent of rivets or bolts, substantially as described. 65

5. In a side frame, the combination of tension member, compression member and strut, said compression and tension members being rolled shapes, an end casting, said tension member fitting an aperture in said casting, and said compression member abutting a portion of the casting, said casting being provided with pedestal jaws between which 75 a journal-box may be accommodated.

6. In a side frame, the combination of rolled or pressed compression and tension members, and an end casting having pedestal jaws, said casting being provided with 80 an aperture through which said tension member is threaded and also provided with a shoulder against which said compression member may abut, substantially as described. 85

7. In a side frame, the combination of rolled or pressed compression and tension members, and an end casting having pedestal jaws, said casting being provided with an aperture of a shape corresponding to the 90 shape of the tension member and with an abutment against which a portion of the compression member may abut, said compression and tension members being bent downward at their ends and secured to said casting, substantially as described.

8. In a side frame, the combination of rolled or pressed compression and tension members, and an end casting accommodating a journal box, said end casting being 100 provided with an aperture in which the tension member is accommodated and with a shoulder against which said compression member may abut, said casting also being provided with a triangular filler extending 105 between the compression and tension members near their ends, substantially as described.

9. In a side frame, the combination of a compression member of channel shape and a 110 tension member of angular shape, and an end casting having pedestal jaws between which a journal box may be accommodated, said casting being provided with an angular aperture adapted to accommodate said 115 tension member and also provided with a triangular filler adapted to lie between said compression and tension members near the ends thereof, substantially as described.

Signed at Granite City, Illinois, this 7 day of April, 1915.

JOHN A. LAMONT.
